UNITED STATES PATENT OFFICE.

WEIDNER J. DENNING, OF ST. LOUIS, MISSOURI.

RADIATOR SHIELD AND DUST COLLECTOR.

Application filed December 13, 1924. Serial No. 755,643.

This invention pertains to radiator shields and dust collectors adapted for mounting over and around heat radiators of any kind or type. It is well known that the dust particles carried in the air currents of a room provided with heating radiators are ordinarily carried up past the radiators and that a large proportion of such dust particles are deposited upon the walls back of the radiators, thereby blackening the walls and rendering them unsightly. It is the primary purpose of the present invention, therefore, to furnish a shield of the kind indicated, with means incorporated thereon for intercepting these said dust particles and causing the same to be deposited in specially provided dust troughs.

In the drawing:

Figure 1 is a side elevation of the improved shield, including the top or cover,

Figure 2 is a top or plan view of the shield the cover being omitted,

Figure 3 is a vertical cross section through the shield and cover, the radiator being indicated in dotted lines.

In constructing my proposed improvement, I provide a casing 1, which is left open at the top and bottom ends as shown at 2, and adapted to sit loosely over and around the ordinary radiator 3. This casing is provided with legs 4 so as to raise it above the floor 5, and permit air currents to pass under the casing and up past the sides of the radiator and finally out at the top of the casing. The upper edges of the casing are bent over inwardly and downwardly towards the radiator 3, so as to form dust stops 6; and the lower edges are bent inwardly and upwardly to form dust troughs 7. It will be noted that the upper dust stops 6 preferably extend inwardly far enough to slightly overlap the outer vertical faces or sides of the radiator 3, while the lower dust troughs 7 are narrower in width than the stops 6, so that they fall short of the sides of the radiator, leaving air spaces or air-ways 8 between the inner edges 9 of the troughs and the radiator. It will also be noted that the inner edges 10 of the stops 6 stand elevated substantially above the top of the radiator 3 so that the air-ways 8 at the sides and ends of the structure are continuous from bottom to top.

The casing 1 is preferably constructed of sheet metal, but any other suitable material may be employed; and the casing as a whole is built to substantially conform to the size

and shape of the radiator. If desired a cover or rest 11 may be provided for the top of the casing. This consists of a sheet of metal or other material having short legs 12, 60 formed with offset feet 13 adapted to engage holes 14 cut through the flange forming the stops 6. The cover 11 which is of greater area than that of the opening defined by the lower edges of the inclined flanges forming 65 the stops 6, is adapted to intercept dust and deflect the same downwardly.

In use, and as the air currents pass up through the air-ways 8, the particles of dust carried in the air currents strike the under sides of the dust stops 6, and are thereby in a large degree intercepted, and either adhere to the stops or losing their momentum, fall back downwardly into the dust troughs 7 or onto the floor, and are thus prevented 75 from lodging upon and soiling the walls of the room, particularly the wall immediately back of the radiator. As a matter of fact, it has been found in actual practice that a very large percentage of the ascending dust intercepted by the stops lodges upon the under side of the stops 6 and is held there by cohesion until removed by means of a damp cloth.

While I have herein described a certain specific method of constructing and assembling the elements of my invention, it is understood same may be varied in minor details, not departing from the spirit of my invention as defined in the appended claims.

Having so described my invention, what I claim as new and patentable is:

1. A device of the kind described, comprising in combination with a heat radiator, a casing adapted to enclose the radiator at the sides and ends, the top and bottom ends of the casing being turned inwardly toward the radiator to form dust stops and dust troughs respectively and means for sustaining the casing in an elevated position relative to the bottom of the radiator.

2. A shield and dust collector for heat radiators, comprising a casing adapted to enclose the radiator at the sides and ends, the upper edges of the casing being turned 95 inwardly and downwardly towards the top of the radiator to form dust stops, and the lower edges being turned inwardly and upwardly to form dust troughs.

3. In a shield and dust collector for a heat radiator wherein is embodied a casing for the sides and ends having inwardly disposed

dust stops at the upper edges thereof; a cover and dust deflector for the top of the casing; and means for mounting the cover and deflector at the top of the casing and in spaced relation thereto.

4. A shield and dust collector for heat radiators comprising a casing adapted to enclose a radiator at the sides and ends except for an air space at the bottom, the upper edges of the casing being turned in-

wardly and downwardly towards the top of the radiator to form dust stops, a cover mounted upon the downwardly and inwardly turned upper edges of the casing and arranged in spaced relation with the same and means at the bottom of the casing for holding the dust.

In testimony whereof I affix my signature.

WEIDNER J. DENNING.
